Primary Examiner — Cathron Brooks*Assistant Examiner* — Teddy Falloway(74) *Attorney, Agent, or Firm* — Quickpatents, LLC;
 Kevin Prince(57) **CLAIM**

I claim the ornamental design for a figurine neck joint, as shown and described.

DESCRIPTION

FIG. 1 is a perspective view of a figurine neck joint, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

1 Claim, 2 Drawing Sheets(56)
